SIGNALING SYSTEM FOR RAILWAY AND
LIKE INSTALLATIONSPaul Nicolas, Paris, France, assignor to Societe
Francaise Radio Electrique, a corporation of
FranceApplication December 4, 1935, Serial No. 52,838
In France December 6, 1934

11 Claims. (Cl. 246—63)

The present invention relates to signaling systems for railway and like installations and is particularly applicable to the repetition of signals in the cabs of locomotives, motor trains and other vehicles travelling on railway tracks of all kinds, whether electrified or not, or insulated or not, and provided with either wooden or metal sleepers.

One object of the invention is to provide a signaling system for railway and like installations of the kind wherein the signals are given under the control of an electrical system which provides for the co-operation between elements stationary along the side of the track and elements carried by the travelling vehicle, but which is of improved construction and operation over the systems hitherto proposed.

Another object of the invention is to provide an improved electrically operated signaling system for railway and like installations involving the co-operation of stationary electrical elements provided along the side of the track with electrical elements carried by the travelling vehicle whereby the operation of the system is obtained by means of electric currents of audio-frequency and without depending upon sharp resonance for the successful co-operation of the electrical elements.

Another and more specific object of the invention is to provide an improved signaling system for railway and like installations whereby a plurality of different signals may be selectively given on the travelling vehicle by means of an electrical system operating by electro-magnetic induction and which provides for the co-operation between elements stationary along the side of the track and elements carried by the travelling vehicle but without depending upon sharp resonance for the successful operation of the co-operating electrical elements.

A still further object of the invention is to provide an improved signaling system for railway and like installations which is adapted to give signal indications on the travelling vehicle by means of an electrical system which provides for the co-operation between stationary elements provided along the side of the track and further elements carried by the moving vehicle, in combination with means for controlling the said signals in accordance with the condition of a track section ahead of the track section on which the travelling vehicle is moving.

In carrying the invention into practice, the improved signaling system according to the invention provides preferably for the indication on the

travelling vehicle itself of signal indications which are normally given by indicators arranged at intervals along the side of the track.

To this end, there corresponds to each signal indicator located at the side of the track, a particular electrical combination which is translated on board the vehicle by an ordinary signal (coloured lamp, bell, horn, or the like) according to a pre-arranged code. This signal is normally produced at the moment when the vehicle passes the corresponding indicator position along the track. It may, furthermore, be so arranged that the signal given on the vehicle persists after the indicator position has been passed and has to undergo a resetting operation carried out by the driver of the vehicle. The production of the signal and this resetting operation may be registered on a band of paper by any known process, for example, mechanical, in order to show that the signal has been properly produced and has been properly noted.

The electrical system operates by induction without mechanical contact between the movable elements of the apparatus and the stationary elements. The stationary apparatus located along the side of the track adjacent to the indicators are composed entirely of inert elements, all the necessary sources of current being carried on the vehicle. In addition to these advantages which are common to other known arrangements, the system according to the invention has also the advantage that the determination of the different signals is not dependent upon sharp resonances necessitating on the part of the source or sources of alternating current used, great stability of frequency. Finally, the system may be so arranged that if the mechanism of the signal indicator ceases to function the indication given on the vehicle is necessarily that of a blocked track.

The number of the separate signals which it is generally desired to repeat on the vehicle is three. However, with the arrangement according to the invention hereinafter to be described there may easily be obtained four distinct indications. It will also be appreciated that there is nothing to prevent a generalization of the system so that it gives a larger number of indications.

The above and further objects, advantages and features of the invention will be more clearly understood from the description of a preferred embodiment thereof, which is given hereinafter, by way of example, with reference to the accompanying drawings, in which:—

tion on the moving vehicle and a circuit arranged at the side of the track,

Figure 2 is a modification of the circuit arranged at the side of the track according to 5 Figure 1.

Figure 3 represents diagrams explaining the operation of the receiver on the vehicle,

Figure 4 shows in detail the diagram of the receiver on the vehicle,

10 Figure 5 shows a further modification of the circuit arranged at the side of the track; and

Figure 6 shows the signal indicating circuits controlled by the receiver.

15 With reference to Figure 1, the signal indicating system comprises:

1. On the vehicle

a. A generator of alternating current G usually 20 of single phase supplying a coil S termed the emitter coil. In series with G and S are arranged various electrical elements such as a condenser C, a rheostat R_h, an ammeter D, etc. in order to regulate and control the intensity of the current supplied by G and also to improve the 25 power factor of the circuit.

A receiver R, which will be more fully described hereinafter, is supplied with current derived from G by means of an impedance I connected in series with G and S.

30 The frequency of the current given by G will preferably be chosen of an average audio-frequency, for example, from 400 to 2,000 periods per second.

b. A coil F termed the receiving coil.

35 Under certain conditions, as will hereinafter be described, the receiving coil F is influenced by the coil S and becomes the seat of an electromotive force. The arrangement is normally such that when S and F are not coupled with other 40 circuits, the electromotive force induced by S in F is small or nil.

The receiving coil F is connected to the receiver R as shown.

c. The receiver R which permits of roughly 45 measuring in value and sign the angle of phase between the electromotive force E induced in F and the primary current I_p supplied by the generator G. The said receiver in turn operates 50 relays which produce on the vehicle desired optical or audible signals.

2. On the ground along the track U

Two fixed coils A and B which, when the vehicle 55 passes close to them, are coupled simultaneously with S and F. It is furthermore possible in many cases to replace the two coils A and B by a single coil provided that this is of sufficient geometrical dimensions to be simultaneously coupled with S and F. Finally, an impedance Z which is of different value according to the signal which it is 60 desired to produce, is connected in parallel with A and B by the mechanism of the track signal indicator.

The different coils S, F, A, B, may be provided 65 or not with iron cores.

The operation of the system will readily be understood with reference to Figure 1.

When the unit carried by the vehicle and 70 formed by the emitter S and the receiver coil F passes in the vicinity of A and B, an induced current is developed in the circuit AB. Owing to the coupling existing between B and F, this induced current influences in its turn the coil F and the receiver R.

75 This being the case, it will be understood that

the phase angle between the current flowing in the coil B and consequently between the electromotive force induced in the coil F and the current flowing in S, the phase of which is taken as a basis, will depend substantially upon the nature 5 and the value of the impedance Z.

In a general manner, the coils A and B will be so constructed as to present a considerable excess potential that is to say that the ratio of their self-induction to their resistance will be such that at 10 the frequency of the current supplied by the generator G, the counter electromotive force due to the self-induction of the coil is in absolute value several times greater than that due to the ohmic resistance. 15

Under these conditions, if no impedance Z is 20 interposed, the current in the coil B will be approximately in phase, for a suitable choice of the directions of winding of the coils, with the primary current flowing in S. 25

If, on the contrary, there is interposed at Z a capacitative reactance of small value compared with the inductive reactance of the coils A and B, the current flowing in B will be approximately in phase opposition with the current in the emitter core S.

If there is interposed, on the other hand, at Z a resistance without appreciable self-induction or capacity and of small value as compared with the reactance of the coils A and B, the current in 30 B will be approximately lagging by a quarter of a period behind the primary current in the emitter coil S.

Finally, in order to cause the current in B to 35 lead by a quarter of a period on the current in S, a slightly more complicated arrangement will be employed which comprises the use of a third coil A₁. The operation of this arrangement will readily be understood with reference to Figure 2. When it is desired to produce this combination, it 40 will be arranged that the mechanism of the track signal indicator connects a small resistance Z₁ in parallel with A and places in circuit instead thereof a third coil A₁ of mechanical and electrical dimensions similar to those of A and located 45 in its immediate vicinity without being strongly coupled therewith. A₁ is wound oppositely to A. In a modification of the same method, a similar operation could be carried out by inserting in 50 the circuit a coil wound in an opposite direction in the place of coil B influencing F. As the circuit would otherwise be identical with that of Fig. 2, except for the opposite winding on the mentioned coil replacing coil B, it is thought superfluous to illustrate such an obvious and slight variation. In either case, it is clear that if Z₁ is a resistance having the same value as in the third case, the desired result will be attained. 55

The problem of the repetition of the signals on the vehicle then resolves into the construction 60 of a device adapted to measure the phase angle existing between the primary current I_p of the emitter S and the electromotive force collected in the coil F. Figure 3 shows the value of this phase angle in the different cases. In this figure, the electromotive force E collected in F is represented by a vector (OE₁, OE₂, OE₃, OE₄, according to whether the first, second, third or fourth case is 65 being dealt with). This electromotive force is, of course, in advance by a quarter of a period on 70 the current in the coil B.

This being the case, let there be drawn on Figure 3 two straight lines X₁O_X, Y₁O_Y at an angle of 45° with respect to OE₁, OE₂, OE₃ and OE₄, and let it be imagined that a suitable electrical ar- 75

5 arrangement actuated both by the primary current I_p and the electromotive force OE , effects the excitation of a relay R_1 when OE is in the half plane below the straight line X_1OX , but this relay 5 is not excited when the vector OE is above this line. Let it be supposed also that a second relay R_2 is excited when the vector OE is below the line YOY_1 but that it is not excited when the vector OE is above this line.

10 It will easily be seen that such relays can be connected to close contacts controlling coloured lamps, bells, etc.

Given the above arrangement, it will now be seen that in the first case above mentioned, this 15 will result in both R_1 and R_2 being de-energized. In the second case, R_1 will be de-energized and R_2 will be energized. In the third case, both R_1 and R_2 will be energized, and in the fourth case 20 R_1 will be energized and R_2 will be de-energized. Three of the above four cases may be made to correspond in any suitable manner to the three signals which it is desired to reproduce. Preferably, the first mentioned case will be chosen to represent the signal "line blocked" so that an 25 accidental failure of current in the relays or a bad contact on the impedance Z will not give any other indication.

30 In Figure 4, there is illustrated by way of example, one manner of constructing the phase selecting device which permits of controlling the relays R_1 and R_2 .

35 In the embodiment illustrated in Figure 4, the receiving coil F is shunted by a condenser C and a resistance r , this arrangement having for effect to select by the known method of resonance or tuning in the circuit of F , the electromotive force E due to the coupling between S and AB with respect to other accidental electromotive forces which may be induced, and also to 40 strengthen the current in the circuit of F . The resistance r will nevertheless be given a value sufficiently small to avoid the resonance being too sharp and the possible variations of frequency of the generator G having an influence on the operation 45 of the arrangement. There is also connected to the terminals of the receiving coil F the primary windings of a transformer T provided with two identical secondary windings. On the other hand, the primary current I_p of the emitter 50 passes through the impedance I which is formed by a self-induction coil L , two resistances r_1 and r_2 and a condenser C_1 all connected in series. The values of L , r_1 , r_2 , and C_1 , may be so chosen 55 that the sums of the potentials at the terminals of L and r_1 on the one hand and of r_2 and C_1 on the other hand, are approximately equal and displaced in phase by ± 45 degrees with respect to the primary current and therefore by 90 degrees between themselves.

60 These potentials supply respectively the primary windings of two transformers T_1 and T_2 , the secondaries of which are formed by two equal half windings which produce potentials of equal value but of opposite phase.

65 It will be seen from the connections of Figure 4 that each of the units formed by the secondary of one of the transformers T_1 or T_2 and one of the secondaries of the transformer T supplies a system of two rectifying devices V (thermionic valve or metallic rectifier). Each of these systems supplies a rectified current to the resistances W shunted by the condensers K . If the different elements of the same name (W or K) are truly equal to one another, it will easily be seen that 70 no rectified continuous potential will appear be-

tween the points M_1 and N_1 for the electromotive force of which the coil F is the seat will have its phase shifted by $+45^\circ$ or -135° with respect to the primary current I_p , because at this moment the tensions introduced into the secondaries of 5 the transformer T_1 by the secondary of the transformer T exactly compensate for the tensions induced in the two halves of the secondary T_1 by the primary of this transformer. In the same way, as regards the difference of potentials between the points M_2 and N_2 , it will be zero when 10 the phase between the electromotive force at F and the current I_p is -45° or $+135^\circ$, because an exact compensation takes place at this moment in the half-secondaries of the transformer T_2 . 15 With suitably selected directions of winding primaries and secondaries of the transformers T , T_1 , T_2 , it can be arranged that there is obtained, for example, at M_1 and N_1 a positive potential when in Figure 3 the vector OE is situated in 20 the half plane below the straight line X_1OX (phase angle less than $+45^\circ$ or -135° , and negative in the contrary case. Corresponding conditions can also be obtained for M_2N_2 and Y_1OY (the tension being positive for example for a 25 phase angle less than -45° or $+135^\circ$).

If the relays R_1 and R_2 were sufficiently sensitive, these could be connected respectively between M_1 and N_1 and M_2 and N_2 . In practice, however, it is found preferable to effect this connection through a triode amplifying valve or a gaseous discharge tube called an ionized-gas grid-controlled relay and which is represented at Th on the drawings. For example, the point M_1 30 will be connected to the grid of the Thyratron valve and N_1 to its cathode. When an ionized-gas grid-controlled relay is employed, it is preferable to connect the point M_1 to the grid through a fairly high resistance r_3 , the resistance of the grid-filament space of an ionized-gas grid-controlled relay being adapted to be small when a considerable current flows between the anode and cathode. 35

40 It will furthermore be noted that by giving sufficiently high values to the capacities K , it is possible to obtain an operation of the arrangement such that these capacities are charged in a short time under the action of the transformers T , T_1 , and T_2 and rectifying elements V , while 45 their discharge through the resistances W only takes place slowly if the resistances W are of high value. This feature is of importance because when the vehicle is travelling at a high speed, the duration of the action between the coils A , B and S , F is small. 50

55 The arrangement is completed by the two relays R_1 and R_2 being excited by the anode current of the ionized-gas grid-controlled relay valve Th , the plate circuit of which is supplied, for example, by the secondary of a transformer T_3 , the primary winding of which is supplied by the generator G . The relays will then operate on failure of current when OE is in the half plane located above X_1OX or YOY_1 . 60

65 Figure 6 represents the circuits controlled by the relays R_1 and R_2 . As shown, the relay R_1 is provided with three armatures 1, 2, 3. The role of the armatures 1 and 2 will be explained more fully hereinafter while the armature 3 which oscillates between two pairs of contacts serves to 70 control the signaling circuits. The relay R_2 is provided with five armatures 4, 5, 6, 7, 8. The armature 4 is utilized in combination with the armature 2 and its operation will be explained more fully hereinafter. The armatures 5, 6, 7, 8 75

together with the armature 3 control the signalling circuits, each armature closing a contact in the position of rest or of working. The signal indicating devices (lamps, horns or the like) are shown at 9, 10, 11, and 12 and are supplied from a suitable source 13. It will be seen from the connections of the contacts of the two relays that when R_1 and R_2 are de-energized, the armatures 3 and 6 close the circuit of the indicating device 11 which then operates. The simultaneous energization of R_1 and R_2 effects the closing through the armatures 3 and 5 of the circuit of the indicating device 12. If the relay R_1 is energized alone and R_2 is de-energized, the armatures 3 and 8 close the circuit of the indicating device 9. Finally, if R_2 is energized and R_1 is de-energized, the armatures 3 and 7 close the circuit of the indicating device 10. Thus, a different indicating device is operated for each combination.

Naturally, in place of the arrangement described, any other means may be employed for detecting the phase of the electromotive force in the coil F with respect to the current I_p . For example, a device similar to a watt meter or the like may be used.

An important application of the signaling arrangement, the principle of which has been explained above, consists in combining the same with the signaling arrangement forming the object of my co-pending application No. 15,962 of 12th April 1935, which device has for its object to reveal the presence in front of the vehicle equipped therewith, of another vehicle the axles of which close the track circuit which is the seat of the currents induced by the emitter of the first vehicle.

The arrangement in said application consists in inducing the current in the rails through a coil similar to S, collecting this current by means of a coil similar to F and measuring by means of a receiver similar to R the phase displacement between the current supplied by a generator similar to G and the current received, this phase displacement being variable with the distance from the short-circuit of the track.

The coils S and F must then be located on the vehicle in such manner as to be coupled with the track circuit as strongly as possible. This modification can naturally only be employed if the track has insulating sleepers and if the joints of the rails are sufficiently electrically conductive.

In this case there will be used three of the four proposed positions of the vector OE for the repetition of the three signals "line clear", "warning", "line blocked", the fourth position corresponding to the operation of the arrangement forming the object of my co-pending application aforesaid.

An interesting advantage of the above described arrangement is that it is then possible to produce the signal "line block" by using the mechanism of the track signal indicator to short circuit the track, which has the advantage that the signal "line blocked" is produced not only on passing the said signal indicator but also at a certain distance before reaching the same.

Nevertheless, when it is desired to carry the said combination into practice, it will be preferable to slightly modify the constitution of the circuit of the coils A and B since otherwise a certain confusion might result between the signal "line blocked" and the signal given by the presence of another vehicle on the track, due to the

impedance of the track circuit then being of a nature similar to that of the simple circuit formed by the coils A and B in series.

To this end, there may then be used, for example, the arrangement according to Figure 5. The coils S and F are coupled, on passing a track signal indicator, with the coils A and B as in Figures 1 and 2. In addition however, they are also strongly coupled with the track indicated at V, which may be short circuited in front of the vehicle by another vehicle or at 14 by a mechanism controlled by another signal indicator or from a signal box. There is connected in series with each of the coils A and B a resistance W_1 and a capacity K_1 of suitable values. The capacity will be chosen in such manner that the unit formed by the self-induction of the coil and the capacity K_1 in series therewith is approximately tuned to the frequency of the current supplied by the generator G. The resistance W_1 serves effectively to damp the system so as to avoid the possible influence of variations of frequency of G. It will readily be understood that in this case, when no impedance Z is connected in the circuit, the electromotive force induced by B in the coil F is in quadrature with that produced by the track current and the two signals "closed line" and "train ahead" cannot therefore be confused. This arrangement will be chosen for the repetition of the signal "line blocked".

By giving a suitable value to Z (capacitative or self-inductance reactance according to the relative sense of the couplings of S and F with the track circuit and with the coils A and B) there may be produced a signal opposite in phase to that which is given by the current in the track circuit. Finally, by using in a similar manner to that of Figure 2, a second coil A_1 of opposite winding to A, there may be obtained a signal in phase opposition to that which corresponds to the "blocked track" (Figure 5). A_1 , like A, will be connected in series with a capacity K_1 and a resistance W_1 , and the impedance Z_1 introduced by the contact controlled by the track signal indicator will be a resistance of small value.

As it is desirable, at least for the most important indications such as "line closed" and "warning", that the signal indication on the vehicle should not disappear as soon as the corresponding track signal indicator has been passed, it will be of advantage to use for one at least of the relays R_1 and R_2 a relay of the type known as "guarded". This term is given to a relay which after having been deenergized cannot become energized again by itself. To effect this, it is sufficient, for example, for the de-energization to close a contact short-circuiting the coil of the relay.

Let it be supposed, for example, that the following code has been adopted:

- 1.—Line blocked: R_1 and R_2 de-energized.
- 2.—Warning: R_1 de-energized, R_2 energized.
- 3.—Line clear: R_1 and R_2 energized.
- 4.—Track current (vehicle in front): R_1 energized, R_2 de-energized.

It will then be of advantage to adopt the arrangement that R_1 is a "guarded" relay and is provided furthermore with a system of contacts such that when R_1 and R_2 are simultaneously de-energized, R_2 also cannot energize itself again. When R_1 is energized, R_2 will not be "guarded". The fourth indication given by the track current

is in fact of a continuous character and is not transitory like that which is produced on passing a track signal indicator.

With reference once more, to Figure 6, it will be understood that this figure shows an arrangement according to the above explanation. The armature 1 of the relay R₁ short-circuits the coil of this latter when it is de-energized. The armature 2 is in series with the armature 4 of the relay R₂. These two armatures close a circuit short circuiting the coil of R₂ when the two relays are de-energized. The arrangement can only be set in operation again when the cause of the de-energization of the relays disappears and the contacts 1, 2, and 4 are opened, for example by hand by means of a push button, not shown.

The principle of the system of the repetition of signals which has just been described may of course be extended to a number of signals greater than four. The vector OE could, for example, be given six positions separated by sixty degrees, by utilizing three relays or any other similar arrangement. It will therefore be understood that the invention is in no way limited to the particular arrangements above described but comprises all modifications thereof within the scope of the appended claims.

What I claim and desire to secure by Letters Patent of the United States is:—

1. A signaling system for railway and like installations in which a vehicle travels along a predetermined track, comprising a first electrical system carried by said vehicle including an alternating current generator, an emitter coil in the circuit of said generator, a receiver coil located so as to avoid inductive coupling with said emitter coil and a receiver connected to be supplied differentially by said generator and by said receiver coil and comprising means for measuring the difference of phase between the electromotive force in said receiver coil and said generator current, and a stationary electrical system located alongside said track and comprising two inductances forming a closed circuit and means for controllably connecting a common impedance in shunt across each of said inductances, said inductances of said stationary system becoming coupled respectively with said emitter and receiver coils of said system carried by said vehicle when said vehicle passes along said track so that an electromotive force is induced in said inductances by said emitter coil, which electromotive force in turn induces an electromotive force in said receiver coil of said first mentioned system which is supplied to said receiver.

2. A signaling system for railway and like installations in which a vehicle travels along a predetermined track, comprising a first electrical system carried by said vehicle including a generator of alternating current of audio frequency, an emitter coil in the circuit of said generator, a receiver coil located so as to avoid inductive coupling with said emitter coil, and a receiver connected to be supplied differentially by said generator and by said receiver coil and comprising means for measuring the difference of phase between the electromotive force in said receiver coil and said generator current and means responsive to an audio frequency current for giving an indication in accordance with said phase-difference, and a stationary electrical system located alongside said track and comprising two inductances forming a closed circuit and means for controllably connecting a common impedance in shunt across each of said inductances, said

inductances of said stationary system becoming coupled respectively with said emitter and receiver coils of said system carried by said vehicle when said vehicle passes along said track, so that an electromotive force is induced in said inductances by said emitter coil, which electromotive force in turn induces an electromotive force in said receiver coil of said first mentioned system which is supplied to said receiver.

3. In a signaling system for railway and like installations in which a vehicle travels along a predetermined track and a signal indication is given by induction between an electrical system carried on said travelling vehicle and a stationary electrical system located alongside said track, said stationary electrical system located alongside said track comprising two inductances forming a closed circuit and means for controllably short circuiting each of said inductances by an impedance.

4. In a signaling system for railway and like installations in which a vehicle travels along a predetermined track and a signal indication is given by induction between an electrical system carried on said travelling vehicle and a stationary electrical system located alongside said track, said stationary electrical system located alongside said track comprising two inductances in series, means for short circuiting each of said inductances by a common impedance and means for additionally inserting in the circuit instead of one of said inductances a further inductance wound oppositely to the said last inductance.

5. In a signaling system for railway and like installations in which a vehicle travels along a predetermined track and a signal indication is given by induction between an electrical system carried on said travelling vehicle and a stationary electrical system located alongside said track, said stationary electrical system located alongside said track comprising at least two inductances in series, means for short circuiting each of said inductances by a common impedance, and a resistance and a capacity connected in series with each of said inductances.

6. A signaling system for railway and like installations in which a vehicle travels along a predetermined track provided with a track signal indicator, comprising a first electrical system carried by said vehicle including an alternating current generator, an emitter coil in the circuit of said generator, a receiver coil located so as to avoid inductive coupling with said emitter coil, and a receiver connected to be supplied differentially by said generator and by said receiver coil and comprising means for measuring the difference of phase between the electromotive force in said receiver coil and said generator current, and a stationary electrical system located alongside said track and comprising at least two inductances in series and means controlled by said track signal indicator for short circuiting each of said inductances by a common impedance and for additionally inserting in the circuit instead of one of said inductances a further inductance wound oppositely to the said last inductance, said inductances of said stationary system becoming coupled respectively with said emitter and receiver coils of said system carried by said vehicle when said vehicle passes along said track, so that an electromotive force is induced in said inductances by said emitter coil, which electromotive force in turn induces an electromotive force in said receiver coil of said first mentioned system which is supplied to said receiver.

7. A signaling system for railway and like installations in which a vehicle travels along a predetermined track provided with electrically insulating sleepers, comprising a first electrical system carried by said vehicle including an alternating current generator, an emitter coil in the circuit of said generator, a receiver coil located so as to avoid inductive coupling with said emitter coil and a receiver connected to be supplied differentially by said generator and by said receiver coil and comprising means for measuring and indicating the difference of phase between the electromotive force in said receiver coil and said generator current, and a stationary electrical system located alongside said track and comprising two inductances and means for controllably connecting an impedance in circuit with said inductances, said inductances of said stationary system becoming coupled respectively with said emitter and receiver coils of said system carried by said vehicle when said vehicle passes along said track, so that an electromotive force is induced in said inductances by said emitter coil which electromotive force in turn induces an electromotive force in said receiver coil of said first mentioned system which is supplied to said receiver, and means for additionally controlling the indications given by said receiver in accordance with the condition of a track section ahead 30 of the track section on which said vehicle operates with said stationary system alongside said track.
8. A signaling system for railway and like installations in which a vehicle travels along a predetermined track provided with electrically insulating sleepers comprising a first electrical system carried by said vehicle including an alternating current generator, an emitter coil in the circuit of said generator, a receiver coil located so as to avoid inductive coupling with said emitter coil and a receiver connected to be supplied differentially by said generator and by said receiver coil and comprising means for measuring and indicating the difference of phase between the electromotive force in said receiver coil and said generator current and means for coupling said coils with said rails so that said receiver also indicates a short circuit of the track section in front of the track section occupied by said vehicle, and a stationary electrical system located alongside said track and comprising at least two inductances in series, a resistance and a capacity in series with each of said inductances, and means for controllably short circuiting each 55 of said inductances by a common impedance, said inductances of said stationary system becoming coupled respectively with said emitter and receiver coils of said system carried by said vehicle when said vehicle passes along said track, so that an electromotive force is induced in said inductances by said emitter coil, which electromotive force in turn induces an electromotive force in said receiver coil of said first mentioned system which is supplied to said receiver.
9. In a signaling system for railway and like installations in which a vehicle travels along a predetermined track and a signal indication is given by induction between an electrical system carried by said travelling vehicle and a stationary electrical system located alongside said track, an apparatus on said vehicle comprising an alternating current generator, an emitter coil in the circuit of said generator, a receiver coil located so as to avoid inductive coupling with 75 said emitter coil, an impedance energized by said generator and comprising a series of partial impedances, the voltages at each of said partial impedances presenting between themselves and with respect to said generator current predetermined phase displacements, a transformer supplied by each of said voltages and having a corresponding number of secondary windings, the extremities of each of said windings of said transformer being connected to a circuit composed of two series connected units each comprising a resistance shunted by a capacity, a connection from the mid point of each of said secondary windings to the junction of the corresponding resistance capacity units, means for introducing into each of said connections a voltage furnished by said receiver 15 coil, and signal indicating means connected to said resistance capacity-unit circuits.
10. In a signaling system for railway and like installations in which a vehicle travels along a predetermined track and a signal indication is given by induction between an electrical system carried by said travelling vehicle and a stationary electrical system located alongside said track, an apparatus on said vehicle comprising an alternating current generator, an emitter coil in the circuit of said generator, a receiver coil located so as to avoid inductive coupling with said emitter coil, an impedance energized by said generator and comprising a series of partial impedances, the voltages at each of said partial impedances presenting between themselves and with respect to said generator current predetermined phase displacements, a transformer supplied by each of said voltages and having a corresponding number of secondary windings, the extremities of each of said secondary windings of said transformer being connected to a circuit composed of two series connected units each comprising a resistance shunted by a capacity, a connection from the mid point of each of said secondary windings to the junction of the corresponding resistance capacity units, means for introducing into each of said connections a voltage furnished by said receiver coil, means for collecting at the output of said receiver a number of voltages representing a predetermined signal, electromagnetic relays controlled in accordance with said voltages, and a circuit comprising a plurality of signal indicators and the contacts on said electromagnetic relays so connected as to render each of said signal indicators operative for a different predetermined combination of energization of said electromagnetic relays.
11. A signaling system for railway and like installations in which a vehicle travels along a predetermined track provided with a track signal indicator, comprising a first electrical system located alongside said track and comprising two inductances and means controlled by said track signal indicator for connecting an impedance in circuit with said inductance, and a second electrical system carried by said vehicle including a generator of alternating current of audio frequency, an emitter coil in the circuit of said generator and a receiver coil located so as to avoid inductive coupling with said emitter coil, so that said inductance of said stationary system alongside said track becomes coupled respectively with said emitter and receiver coils of said system carried by said vehicle when said vehicle passes along said track, whereby an electromotive force is induced in said inductances by said emitter coil, which electromotive force in turn induces an electromotive force in said receiver 75 coil.

coil of said first mentioned system which is supplied to said receiver, a receiver supplied differentially by said generator and by said receiver coil and comprising means for measuring the difference of phase between the electromotive force in said receiver coil and said generator current and means responsive to an audio frequency current for giving an indication in accordance with said phase difference, said two last mentioned means comprising an impedance energized by said generator and comprising a series of partial impedances, the voltages at each of said partial impedances presenting between themselves and with respect to said generator current predetermined phase displacements, a transformer supplied by each of said voltages and having a corresponding number of secondary windings, the extremities of each of said secondary windings of said transformer being connected to a circuit

composed of two series connected units each comprising a resistance shunted by a capacity, a connection from the mid point of each of said secondary windings to the junction of the corresponding resistance capacity units, means for introducing into each of said connections a potential drop furnished by said receiver coil, means for collecting at the output of said receiver a number of voltages representing a predetermined signal, grid controlled valve relays supplied respectively by said voltages, electromagnetic relays controlled by said ionized gas valve relays and a circuit comprising a plurality of signal indicators and the contacts of said electromagnetic relays so connected as to render each of said signal indicators operative for a different predetermined combination of energization of said electromagnetic relays.

PAUL NICOLAS.
